UNITED STATES PATENT OFFICE

168,991

FRONT FOR SPECTACLE FRAMES

Mac Gerlich, Brooklyn, N. Y.

Application April 25, 1952, Serial No. 19,473

Term of patent 7 years

(Cl. D57—1)

To all whom it may concern:

Be it known that I, Mac Gerlich, a citizen of the United States, residing at Brooklyn, New York, in the county of Kings, city and State of New York, have invented a new, original, and ornamental Design for a Front for Spectacle Frames, of which the following is a specification, reference being had to the accompanying drawing, forming part hereof.

Figure 1 is a front elevational view of a front for spectacle frames, showing my new design.

Figure 2 is a front elevational view on an enlarged scale of the element of ornamentation shown in full lines in Figure 1, and

Figure 3 is a side elevational view of the element of ornamentation shown in Figure 2.

The essential features of my design for a front for spectacle frames reside in the ornamentation thereof shown in full lines.

I claim:

The ornamental design for a front for spectacle frames, as shown and described.

MAC GERLICH.
